UNITED STATES PATENT OFFICE

124,920

DESIGN FOR A BOTTLE

Philip Ignatius Heuisler, Jr., Baltimore, Md., assignor to Maryland Glass Corporation, Baltimore, Md., a corporation of Maryland

Application November 23, 1940, Serial No. 96,760

Term of patent 14 years

To all whom it may concern:

Be it known that I, Philip I. Heuisler, Jr., a citizen of the United States and a resident of Baltimore, State of Maryland, have invented a new, original, and ornamental Design for Bottles, of which the following is a specification.

Reference is had to the accompanying drawing forming part thereof, in which:

Figure 1 is a perspective view of a bottle, showing my new design.

Figure 2 is an end elevation thereof.

Figure 3 is a plan view.

Figure 4 is a cross section taken on the line 4—4 of Fig. 1.

The dominant features of my design reside in the parts shown in solid lines.

I claim:

The ornamental design for a bottle, as shown and described.

PHILIP IGNATIUS HEUISLER, JR.
